(57) **CLAIM**

The ornamental design for a pear-shape faceted gemstone crown, as shown.

DESCRIPTION

FIG. 1 is the top view of a pear-shaped faceted gemstone crown showing my new design;

FIG. 2 is a left side view thereof, the right side being a mirror image;

FIG. 3 is a rounded end view thereof; and,

FIG. 4 is a pointed end view thereof. The pavillion is shown in broken lines in FIG. 2, FIG. 3, and FIG. 4 for illustrative purposes only and forms no part of the claimed design.
